AUGUST C. MEHRTENS, OF MILWAUKEE, WISCONSIN.

ROTARY VALVE STRUCTURE FOR INTERNAL-COMBUSTION ENGINES.

1,411,449.

Specification of Letters Patent.

Patented Apr. 4, 1922.

Application filed March 19, 1919. Serial No. 283,548.

To all whom it may concern:

Be it known that I, AUGUST C. MEHRTENS, a citizen of the United States, residing at Milwaukee, in the county of Milwaukee and State of Wisconsin, have invented certain new and useful Improvements in Rotary Valve Structures for Internal-Combustion Engines, of which the following is a specification.

The disadvantages, both from structural and operating standpoints, of poppet and sleeve inlet and exhaust valves for automobile, truck, aeroplane, and other internal-combustion engines are well known, the desirability for suitable rotary valves of this kind being more or less equally appreciated. Accordingly, the main or leading object of my invention is the provision of a rotary or similar valve structure which overcomes and avoids the several objections previously raised, not without legitimate basis, against valves of this type and style. My purpose is to supply a valve construction which is capable of being machined or finished with ease, durability, and economy, and consequently of moderate manufacturing cost, which may be operated effectively over a large range of speeds and with the expenditure of but a small amount of power, which will distribute full even charges of the explosive gaseous mixture to all of the various companion engine cylinders, which will effect a more complete discharge of the exploded or spent gases than has heretofore been possible, thus keeping the cylinders well scavenged, which will have but comparatively little pressure exerted on its bearing surfaces, which will have long life and afford sustained horsepower, and which will run smoothly and silently. My improved valves are so constructed that they have no cams or eccentricities, springs, tappets, or heavy reciprocating sleeves, and will not hammer, warp, burn out, or vibrate. Furthermore, such novel valves will not require adjustment or regrinding, nor will they stick from heating or warping, and there will be no appreciable gas leakage around them.

In order that those skilled in this art may understand and hence appreciate the numerous important advantages of a structure of this new character possessing the above and other desirable qualities, I have illustrated in the accompanying drawing, throughout the various views of which like reference characters refer to the same parts,

a simple and desirable embodiment of the invention, but it is to be understood that the latter is susceptible of a variety of embodiments and is not limited to the precise and exact details of structure presented, because these may be varied within wide limits without departure from the substance and essence of the invention and without the sacrifice of any of its substantial benefits and advantages.

In this drawing:

Figure 1 is a fragmentary, vertical, cross-section through one cylinder of a multi-cylinder internal-combustion engine or motor equipped with my improved type of separate and independent rotary inlet and exhaust valves;

Figure 2 is a longitudinal, substantially horizontal section on line 2-2 of Figure 1;

Figure 3 is another fragmentary or partial lengthwise section on line 3-3 of Figure 1.

Although only a small part of one cylinder 10 of the engine or motor and a fragment of each reciprocating piston 11 are shown in this drawing, it is to be borne in mind that the appliance has a plurality of aligned cylinders and pistons as is customary, and that these are provided with separate intake and discharge valves, all of the inlet valves being in register and rotated one through or by the other, the exhaust valves being similarly arranged and actuated. Consequently, only one inlet and one exhaust valve appear in Figure 1, although one complete valve or valve section and portions of the valves associated with its opposite ends are shown in Figure 2.

As is illustrated, the cylinders are water-jacketed at 12 for the usual cooling purpose, and each cylinder at its top end has an inlet port 13, converging somewhat downwardly by being beveled or rounded off at 14 and an exhaust or discharge port 15 tapering somewhat upwardly by being rounded or curved at 16. As will be readily understood the easing or rounding off of these walls of such passages facilitates the flow 105 of gases therethrough in their proper direction of travel.

The articulated or sectional admission valve structure comprises a number of aligned, associated or coupled cylindrical valves 17, one for each cylinder, these registering members being rotated at one-quarter

of the engine or crank-shaft speed through or by one another, the end one being driven from the engine or motor crank-shaft in any approved manner not deemed necessary to illustrate. The combination valve structure is revoluble in a cylindrical bearing 18 surrounded by the liquid of the water-jacket. These valves are hollow as illustrated and at each end each has a pair of diametrically-opposite substantially semi-spherical cavities 19 (Figure 2) registering with like recesses in the adjacent end of the next valve. So far as this coupling feature is concerned both the inlet and discharge valves are alike so that the showing in Figure 2 in this respect suffices for both types of valves. Employed as a driving or power-transmitting means between the valves and also permitting such valve-members or sections to rock on one another or tilt slightly with relation to one another to compensate for any unequal heating or tendency to warp I employ a pair of balls 20, 20 seated in such sockets 19, 19. Thus, the rotation of each valve is transmitted to the next one through such coupling or connecting balls, and in turn and by like means such driven valve section or member rotates the next, and so on. Cores are used for the production of these hollow valves requiring the presence of the end holes 21 which, in the finished valves, are closed by plates 22.

Each of these valves has through it a transverse or diametrical port 23 of substantially the same length as the corresponding cylinder port 13, the valve passage being of minimum cross-sectional dimensions, that is, narrowest and shortest, at its center 24 flaring therefrom in opposite directions both lengthwise and crosswise the valve, all as is clearly shown. Above the valve, that is, above each cylinder of the motor, the wall of the structure has an inlet port 25 converging toward the valve, the walls of the port being surrounded by the water of the jacket. This shape or form of the gas ports or passages assures a full charge of gas reaching each cylinder, since its flow through them to the cylinders is facilitated by their shapes or rounded conformations. Furthermore, it should be noted that the outer port 25 is materially wider than the corresponding cylinder port 13, thus insuring the use of the latter to its full capacity. Inasmuch as the mouths or ends of the rotary valve port 23 are wider than the stationary engine port with which it coacts the period of opening of the latter may be made whatever is desired by suitably designing the parts.

As is fully illustrated, the exhaust port 26 is similar to the admission port 25, but is reversely flared or tapered, thus not only aiding the discharge flow of the hot spent gases from the motor, but also lengthening the

time period of the opening of the exhaust. The aligned interconnected discharge valves 27 are much like the inlet valves and as previously stated are connected together and driven in similar manner. The aperture 28, through the exhaust valve, is straight and of uniform cross-sectional rectangular dimensions approximating those of the outlet engine port 15, but is fitted with a renewable or removable protective liner or shell 29 which has through it a centrally constricted passage 30 of substantially the same shape as that of the inlet valve and for a similar purpose. This liner, in order to permit it to freely expand and contract, twist, warp, or otherwise become distorted in shape under the high heat to which it is subjected, is held in place by a single transverse screw 31 extended through the wall of the valve and into a cavity in the liner. This arrangement also affords a simple, efficient means for maintaining the liner shell or sleeve in place and permitting its ready removal or replacement. If desired, although it is not in all cases required, a shell 32 or tube of heat-insulation material may be interposed between the valve opening or port and its lining. It is to be remembered, nevertheless, that a fair share of the heat transmitted by the hot escaping gases to such liner must in turn be conducted away from it otherwise it will become unduly heated. To meet this condition, in part at least, the hollow valve is provided with centrally-arranged opposite webs 33 and 34 connecting the walls of the passage 28 with the outer cylindrical wall. By employing such webs or connecting walls, through one of which the screw 31 extends, the heat is comparatively uniformly transmitted or conducted to the outer cylindrical wall of the valve and hence the tendency to unequal expansion and warping or twisting is in a large measure, if not entirely, overcome.

As in the case of the admission valve, the combined or coupled exhaust valves rotate in a bearing the wall 35 of which is surrounded by the water in the cooling jacket whereby the heat of the exhaust valves is in time carried by the water to the engine radiator where it is cooled in the usual way. As was the case with the inlet or admission valves these discharge valves are rotated by suitable driving means (not shown) driven directly or indirectly from the main engine or crank-shaft.

A slight amount of lengthwise play is provided between the valves of the whole valve system, especially the exhaust valves, whereby to permit them to expand longitudinally without becoming tight or binding in their bearings, and, of course, owing to the independence of the valves or due to their sectional or articulated construction any tendency for them to depart from true align-

ment is permitted and hence sticking of the valves in their bearings is prevented.

It is necessary to maintain a compression-tight relation between the valves and between them and their cylindrical bearings. This is accomplished by delivering oil under pressure or forced to the bearings through pipes 36, 36 and passages 37, 37 to the walls at the points where the joints are between the valves whereby the oil is forced into the small spaces between the ends of the valves, thereby maintaining a pressure-tight but nevertheless yieldable connection between them. Furthermore, adjacent to the cylinder and engine ports of each valve and just beyond such ports, taking into account the direction of rotation of the valves, the bearing has lengthwise grooves, 38, 39, for the exhaust valves and 40 and 41 for the inlet valves, extended substantially the full length of each valve and to which oil under pressure is fed through pipes 42, 43, 44 and 45. Thus, the oil from these various supplies delivered under pressure and hence fed freely to the points desired forms films and seals the valves in their bearings in a compression-proof manner preventing escape of the gas under full pressure. It should be observed, furthermore, that the rotation of the valves spreads the oil fed to the bearing at the points indicated in the form of a film through its entire length thus acting not only as a lubricant but also as a pressure-tight filling.

Having described in detail the various parts of this valve structure it should be noted that in the case of the inlet valve and also the exhaust valve the cylinder ports 13 and 15 respectively have the proper calculated dimensions and these should preferably be narrow since their area determines the gas pressure on the valves. With the upper engine port and the rotary valve port both wider than the corresponding cylinder port, when the latter is open a small amount, the other ports are open much more, whereby the only restriction to the flow of gases resides in the cylinder port, thus affording the maximum volume of gas flow with resulting large power. The rounding or curving of the gas passages assures easy flow without undue retardation due to friction or wire drawing and the avoidance of unnecessary eddy currents, and the valve in each case is open fully for a considerable period of its opening.

It will be appreciated, furthermore, that all of the parts which might otherwise be subject to excessive heating are fully protected by the water-jacket which surrounds the valves and the ported walls, and that the hot gases are in large measure kept away from the valve seat or bearing surface to which the lubricating and pressure-sealing oil is fed in proper quantity under pressure,

the oil delivered at the joints between the valves working its way in both directions along the length of each valve, thus supplementing that supplied to the longitudinal grooves in the bearing, the oil from all sources by the rotation of the valves being spread between the surfaces in the form of a film which performs the sealing or filling function as well as that of lubrication. It will be understood that each valve has oil fed to it at four places, thus assuring a uniform continuous and uninterrupted thin film or layer between the parts.

By having the valve ports extended directly across the valve the hot exhaust gases are disposed of and discharged as quickly as possible thus reducing to a minimum the amount of heat which they transmit to the various elements with which they come in contact. In this way also such gases are kept away from the valve seat or bearing.

It is to be remembered that whereas a specific embodiment of the invention has been presented in detail the invention is not limited to such particular embodiment since in its broader aspect it is susceptible of incorporation in appliances varying widely in structural characteristics. The appliance illustrated and described is merely presented by way of example remembering that to those skilled in this art various minor changes will doubtless suggest themselves without departing from the main features and principles of the invention.

I claim:

1. In a rotary valve structure of the character described for internal-combustion engines and the like, the combination of a cylindrical bearing, a plurality of cylindrical valves in said bearing coupled together end to end whereby they may be rotated by one another, and means to feed a liquid directly to the joints between the valves, substantially as described.

2. In a rotary valve structure of the character described for internal-combustion engines and the like, the combination of a cylindrical bearing, a plurality of cylindrical valves in said bearing coupled together end to end whereby they may be rotated by one another, and means to force a liquid under pressure into the joints between the valves, substantially as described.

3. In a rotary valve structure of the character described for internal-combustion engines and the like, the combination of a plurality of valves coupled together end to end whereby they may be rotated by one another, and means to force a lubricant under pressure directly into the joints between the valves, substantially as described.

4. In a rotary valve structure of the character described for internal-combustion engines and the like, the combination of a cylindrical bearing, a plurality of cylindrical

- valves in said bearing coupled together end to end whereby they may be rotated by one another, means to force a lubricant under pressure directly into the joints between the 5 valves, and means to force a lubricant under pressure into the bearing to create a compression-proof film between the cylindrical surfaces of the valves and bearing, substantially as described.
- 10 5. In a rotary valve structure of the character described for internal-combustion engines and the like, the combination of a cylindrical bearing, a plurality of cylindrical valves in said bearing arranged end to end, 15 driving couplings between the ends of said valves whereby they may be rotated by one another, said couplings being constructed to permit said valves to shift out of alignment, and means to force a liquid directly into the 20 joints between said valves, substantially as described.
6. In a rotary valve structure of the character described for internal-combustion engines and the like, the combination of a cylindrical bearing, a plurality of cylindrical valves in said bearing arranged end to end, driving couplings between the ends of 25 said valves whereby they may be rotated by one another said couplings being constructed to permit said valves to shift out of alignment, means to force a liquid lubricant directly into the joints between said valves, and means to force a liquid lubricant and thereby create a compression-proof film between the surfaces of said valves and bearing, substantially as described.
7. In an appliance of the character described, the combination of a ported internal-combustion engine, a cylindrical bearing, a 40 cylindrical rotary valve in said bearing, said valve having a port extended directly transversely therethrough and co-operating with the ports of said engine, said valve port having a constricted intermediate portion 45 with enlarged ends, the walls of said valve-port being curved from said constricted point to its opposite ends, means to force a lubricant under pressure into said bearing to create a compression-proof film between the cylindrical surfaces of the valves and bearing, and means to force a lubricant under pressure to the ends of said valves, substantially as described.
8. In an appliance of the character described, the combination of a ported internal-combustion engine, a cylindrical bearing, a plurality of rotary cylindrical independent valves in said bearing coupled together end to end whereby they may 55 be rotated by one another, said coupling being constructed to permit said valves to shift out of alignment, each of said valves having a port extended directly transversely therethrough and cooperating 60 with ports of the engine, and means to feed 65

a lubricant under pressure directly into the joints between said valves, substantially as described.

9. In an appliance of the character described, the combination of a ported internal-combustion engine, a bearing, a rotary valve in said bearing having a passage extended directly transversely therethrough, and a liner removably mounted in said passage and having a port intermediately constricted and flaring toward both ends co-operating with the ports of said engine, substantially as described.

10. In an appliance of the character described, the combination of a ported internal-combustion engine, a bearing, a rotary valve in said bearing having a passage extended directly transversely therethrough, and a liner removably mounted in said passage free to expand in any direction, said liner having an intermediately constricted port flaring toward both ends cooperating with the ports of said engine, substantially as described.

11. In an appliance of the character described, the combination of a ported engine, a bearing, a rotary valve in said bearing having a passage extended directly transversely therethrough, a liner in said passage having a port cooperating with those of said engine, and a single screw removably maintaining said liner in position in said passage, substantially as described.

12. In an internal-combustion engine of the character described, the combination of a bearing having gas ports leading thereto and therefrom and tapered in the direction of the gas flow therethrough with converging curved walls, and a valve revoluble in said bearing having a port with a curved wall extended directly transversely therethrough and cooperating with said bearing ports, substantially as described.

13. In an internal-combustion engine of the character described, the combination of a bearing having ports leading thereto and therefrom and tapered in the direction of the gas flow therethrough, and a valve revoluble in said bearing having a port extended directly transversely therethrough and adapted to cooperate with said bearing ports, said valve port having a constricted intermediate portion with enlarged ends, substantially as described.

14. In a construction of the character described, the combination of an internal-combustion engine including its cylinder, a bearing, the cylinder and bearing being connected by a gas-port, the engine also having a second gas-port in communication with said bearing and of greater cross-sectional area than said cylinder-port, both of said ports converging in the direction of gas flow therethrough, and a valve rotatable in said bearing having a port extended directly 120

transversely therethrough cooperating with said cylinder and engine ports and having a constricted intermediate portion of substantially the same cross-section as the narrow portion of one of said ports, substantially as described.

15. In a construction of the character described, the combination of an internal-combustion engine including its cylinder, a bearing, the cylinder and bearing being connected by a gas-port, the engine also having a second gas-port in communication with said bearing and of greater cross-sectional area than said cylinder port, both of said ports

10 having curved walls converging in the direction of gas flow therethrough, and a valve rotatable in said bearing having a port with curved walls extended directly transversely therethrough cooperating with said cylinder

15 and engine ports and having a middle con-

stricted intermediate portion of substantially the same cross-sectional area as the narrow portion of said first port, substantially as described.

16. In a construction of the character described, the combination of an internal-combustion engine including its cylinder, a bearing, the cylinder and bearing being connected by a gas port, the engine also having another gas port in communication with said bearing and of greater cross-sectional area than said cylinder port, both of said ports converging in the direction of the gas flow therethrough, and a valve rotatable in said bearing having a port extended directly 30 transversely therethrough cooperating with said cylinder and engine ports and having a constricted intermediate portion, substantially as described.

AUGUST C. MEHRTENS.
